[57] CLAIM

The ornamental design for a liquid tank for use in the cooling cycle of an air conditioning device or the like, as shown and described.

DESCRIPTION

FIG. 1 is a front elevational view of a liquid tank for use in the cooling cycle of an air conditioning device or the like, showing my new design;

FIG. 2 is a back elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top, front perspective view thereof.

FIG. 1

FIG. 2

FIG. 3

FIG. 4

FIG.5

FIG.6

FIG. 7
